Primary Examiner — Mary Ann Calabrese(74) *Attorney, Agent, or Firm* — Faegre Baker Daniels LLP(57) **CLAIM**

The ornamental design for a conference table, as shown and described.

DESCRIPTION

FIG. 1 is a front perspective view of a conference table according to a first embodiment of my new design; FIG. 2 is a side view thereof; the opposite side is identical thereto; and,

FIG. 3 is an end view thereof; the opposite end is identical thereto.

The conference table is shown with a symbolic break in its length. The appearance of any portion of the article between the break lines forms no part of the claimed design.

Features shown in dashed lines form no part of the claimed designs.
